UNITED STATES PATENT OFFICE

2,315,719

CAR DOOR

Thorvald Madland, Chicago, Ill., assignor to The Youngstown Steel Door Company, Cleveland, Ohio, a corporation of Ohio

Application April 30, 1940, Serial No. 332,507

12 Claims. (Cl. 20—22)

This invention relates to car doors and more particularly to double sliding doors of railway house cars.

It is an object of this invention to provide double doors for railway house cars so related and associated with the cars that substantial unity of movement of the doors under impact is obtained and stresses upon the lock fastening the doors together reduced.

A further object is to provide novel abutment means for the double doors of railway house cars which shall afford a substantial stop for the doors without interfering with unity of movement thereof under impact, the abutment means being so designed as to eliminate castings in its production.

A further object is to provide novel abutment means for the double doors of railway house cars which shall be capable of association with the door track so as to relieve the fastening means for the abutment means of stress.

A further object is to provide novel abutment means for the double doors of railway house cars which shall afford a substantial stop for said doors and provide means for limiting opening movement of one of the doors without locking said door or interfering with the unity of movement of the doors under impact.

Other objects of the invention will become clear as the description thereof proceeds.

In the drawings forming part of this specification:

Fig. 1 is a fragmentary elevation illustrating the upper adjacent portions of double doors of a railway house car and their relationship with the car side.

Fig. 2 is a vertical section taken on line 2—2 of Fig. 1.

Fig. 3 is a fragmentary elevation illustrating the lower adjacent portions of the doors shown in Fig. 1, the abutment member for the doors and their relationship with the car side.

Fig. 4 is a vertical section taken on line 4—4 of Fig. 3.

Fig. 5 is a horizontal section taken on line 5—5 of Fig. 3.

Fig. 6 is a view similar to Fig. 3 showing a modified form of abutment member.

Fig. 7 is a vertical section taken on line 7—7 of Fig. 6.

Fig. 8 is a view similar to Fig. 3 showing another form of abutment member.

Fig. 9 is a vertical section taken on line 9—9 of Fig. 8.

Referring first to Figs. 1 to 5 inclusive which 55

illustrate one embodiment of the invention, there is shown the main and auxiliary doors 10 and 11 of a double door construction for railway house cars. The doors 10 and 11 may be of any desired construction. The doors illustrated are of well-known construction and include a metallic panel 12 formed with spaced horizontal corrugations 13 and marginal vertical corrugations 14. The marginal portions of each of the doors are suitably reinforced by means of upper and lower backing plates 15 and 16. The front vertical margin of the main door 10 is reinforced by means of a vertical backing plate 17 and a channel shaped stiffening member 18. The front vertical margin of the auxiliary door 11 is reinforced by means of a substantially Z-shaped member 19 and a post 20 secured to the inside of the door and cooperating with the member 19 to provide a recess 21 which receives the front edge of the main door when the doors are in closed position. The upper margin of each of the doors is reinforced by means of an angle member 22, the horizontal flange 23 of which extends inwardly into overlapping relationship with a substantially J-shaped header 24 secured to the depending leg 25 of a substantially Z-shaped side plate 26. The upper margins of the main and auxiliary doors are retained by means of a retaining and guiding member 27 fastened to the depending leg 25 of the side plate. Weather protection for the upper portions of the doors at their meeting edges is provided by means of a substantially Z-shaped member 28 fastened to the depending leg 29 of the door retainer 27. The lower margin of each of the doors 10 and 11 is reinforced by means of an angle member 30, the lower horizontal leg 31 of which extends outwardly and is adapted to rest upon the door track 32 for frictionally supporting the doors in lowered position.

The doors are of the type known as lift doors which as more clearly illustrated in Figs. 3 and 4 of the drawings are seated frictionally upon the track 32 when lowered. With this type of door, mechanism not shown is provided for elevating the doors above the track and supporting them upon rolling means for movement upon the track. Any desired mechanism of this character may be employed.

It is common in double door construction to utilize locking means extending across the meeting edges of the doors for fastening them together. Any desired locking means may be used for this purpose.

In order to obtain substantial unity of move-

ment of the doors in a plane parallel to the car side when the cars to which they are applied are subjected to impact so that the locking means employed for the doors is relieved of stress injurious to said means, the considered embodiment of the invention utilizes a substantially Z-shaped member 33 fastened to the depending flange 25 of the side plate 26. The web 34 of this member extends outwardly below the side plate and J-shaped header 24 so that the flange 35 thereof lies in proximity to the upper portions of the main and auxiliary doors at their meeting edges for the purpose of excluding both direct and reflected light from entering the car at the indicated point. The upstanding flange 36 of the Z-shaped member by means of which fastening of the member to the side plate is secured is provided with an inwardly projecting indenture 37. Cooperating with the indenture 37 is a vertical flange 38 formed on a member 39 secured to the upper margin of the auxiliary door post 20. By virtue of this cooperation the auxiliary door is drawn inwardly toward the car side as the door approaches its final closed position. In this position it will be observed that the vertical flange 38 lies inwardly of the indenture 37 and is free for movement in a plane parallel to the car side.

The purpose hereinabove set forth is secured at the lower margins of the doors as well. To this end in the embodiment considered a member 40 is fastened to the reinforcement 41 for the side sill 42 of the car underframe. The member 40 is rolled and is Z-shaped in section and embodies the depending attaching flange 43, the outwardly extending web 44 and the vertical flange 45 which extends above the door track 32 as illustrated in Fig. 4 of the drawings. The upstanding flange 45 lies outwardly of the depending vertical leg 43 of the track and to secure this disposition the vertical leg 46 is coped as indicated at 47 to permit passage of the web 44. In order to properly dispose the member 40 the attaching flange 43 is passed through the cope 47 from the outside and the member then turned through 90° so as to bring the attaching flange 43 into proper engagement with the reinforcing channel 41 for attachment thereto. It is preferred that the web 44 be welded to the vertical flange 45 of the track around the cope 47 therein as indicated at 48 so as to cause the track to absorb stresses incident upon the member 40 and thereby relieve the means for fastening the member 40 to the reinforcing channel 41 of such stress.

The upstanding flange 45 of the member 40 serves as an abutment flange for limiting closing movement of the auxiliary door. Cooperating with the abutment flange for the purpose indicated is a casting 49 secured to the lower forward corner of the auxiliary door 11. This casting is secured to both the vertical and horizontal margins of the door as by means of rivets 50 and 51. The lower portions of the casting 49 is in the form of a pocket 52 formed by means of the inner and outer spaced walls 53 and 54 and the end wall 55. By this construction, the abutment flange 45 is permitted to enter the pocket 52 as the auxiliary door approaches its final closed position and limit closing movement of the door when elevated by engaging the end wall 55.

Rising from the web 44 of the member 40 is a lug 56 formed from a portion of the upstanding flange of the Z-shaped member 40. As clearly shown in Figs. 3 and 5 of the drawings, the lug

56 is spaced from the abutment flange 45 and when the auxiliary door is in its closed and lowered position is received within a recess 57 formed in the casting 49 secured to the auxiliary door. In this position of the door the wall 58 of the lug is spaced a predetermined distance from the vertical wall 59 of the recess 57. It has been found by actual test that a spacing of $\frac{1}{2}$ inch is satisfactory.

The lower forward corner of the main door 10 carries a casting 60 provided with an outwardly extending flange 61 which extends across the abutment flange 45 of the member 40 when the door is in closed position.

In view of the construction at the lower margins of the doors hereinabove described unity of movement of the main and auxiliary doors in a plane parallel to the car side wall is obtained for the lower portions of the doors as well as for the upper portions of the doors. Under impact to the cars to which the doors are applied the doors will rise in a plane parallel to the car side upon their front or rear lower corners depending upon the direction of movement of the cars at the time that impact occurs. The construction hereinabove described does not prohibit this movement of the doors and it is to be observed particularly that the lug 56 permits such movement by reason of the space between its wall 58 and the wall 59 of the casting 49. The lug 58, however, is utilized to limit the opening movement of the auxiliary door when it is in lowered position and unlocked. It is desired at times that loading or unloading of a car proceed through the main door opening only and that the auxiliary door remain closed. The lug 56 insures that the auxiliary door cannot be moved open accidentally a distance greater than the space between the walls 58 and 59.

The disposition of the flange 61 of the casting 60 secured to the lower forward corner of the main door relative to the abutment flange 45 insures against injury to the door post and post strip and sealing strip commonly used upon doors of this character at their rear edges. Where impact occurs at the left hand end of the car as viewed in Fig. 3 of the drawings, the main door will rise about its lower forward corner and effect engagement between the post strip and sealing strip, tending to imposing severe stresses thereon. The cooperation between the flange 61 of the abutment flange 45 is effective to relieve these parts of the indicated stresses.

A modified form of the member 40 is illustrated in Figs. 6 and 7 of the drawings. The member there disclosed embodies a substantially channel shaped member 62, the leg 63 of which is fastened to the channel reinforcement 41. The web 64 of the member 62 extends outwardly and the outer leg 65 of this member extends downwardly and preferably outwardly from the web. A member 66 has an attaching flange 67 by means of which it is secured to the outer leg 65 of the channel member 62. The member 66 has a portion 68 which rises above the track 69 and extends through a cope 70 formed in the horizontal leg 71 of the track. The portion 68 of the member 66 is preferably welded to the track around the cope therein for the purpose hereinbefore set forth.

The upstanding portion 68 embodies an abutment flange 72 which cooperates with a casting 73 secured to the lower forward corner of the auxiliary door 11 and of substantially the same construction as the casting 49 to limit closing movement of the auxiliary door. The portion 68 has,

moreover, an upstanding lug 74 which is spaced from the wall 75 of the recess 76 provided in the casting 73 when the auxiliary door is in its closed position. The lug 74 thereby does not interfere with the movement of the door in a plane parallel to the car side when the car is subjected to impact. In this embodiment of the invention the main door 10 is provided with a casting 69 secured to the lower forward corner thereof for the purpose set forth in the consideration of the first embodiment of the invention.

Another form of the invention is illustrated in Figs. 8 and 9 of the drawings. In this embodiment a substantially channel shaped member 77 whose web 78 is secured to the channel sill reinforcement 41 is utilized. The upper leg 79 extends outwardly while the lower leg 80 extends outwardly and is provided with a downwardly extending flange 81. To this flange a member 82 is secured. The member 82 extends upwardly above the leg 79 through a cope 83 formed in the leg. The portion of the member 82 which lies above the leg 79 provides an abutment flange 84 for limiting closing movement of the auxiliary door. The flange 84 is preferably welded to the leg 79 in the cope 83.

The leg 79 which is a continuation of the sections of the track 69, as clearly appears from Fig. 8 of the drawings, carries an upstanding lug 85. The lug is preferably secured to the leg 79 by being inserted in a cope 86 formed in the leg and welded to the leg around the cope.

A casting 87 is secured to the lower forward corner of the auxiliary door and is provided with a pocket 88, the end wall 89 of which engages the abutment flange 84 to limit closing movement of the auxiliary door. The bracket 87 is provided with a recess 90 having a vertical wall 91 spaced from the upstanding lug 85 when the door is in closed position.

The casting 60 is provided at the lower forward corner of the main door.

The member 39 secured to the upper portion of the auxiliary door post 20 and the Z-shaped member 33 fastened to the depending leg 25 of the side plate 26 are utilized with each of the embodiments of the invention illustrated in Figs. 6 to 9 inclusive.

The cooperation between the several parts of the embodiments illustrated in Figs. 6 to 9 inclusive and the results obtained thereby are the same as described for the embodiment of the invention illustrated in Figs. 1 to 5 inclusive.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. As an article of manufacture, a fabricated member for a railway house car having a supporting track and main and auxiliary sliding lift doors supported upon said track, said fabricated member having a vertical flange adapted to be secured to the underframe of said car, a flange extending outwardly from said vertical flange and spaced stop flanges, one of said stop flanges being adapted to engage said auxiliary door when elevated to limit closing movement thereof, the other of said stop flanges being spaced rearwardly from said first mentioned stop flange and being adapted to engage said auxiliary door when low-

ered and unlocked to permit opening movement thereof to a predetermined amount.

2. As an article of manufacture, a rolled Z member for a railway house car having a supporting track and main and auxiliary sliding lift doors supported upon said track, said member comprising a depending vertical flange adapted to be secured to the underframe of said car, an outwardly extending web and an upstanding flange, said latter flange having a portion thereof cut away to provide an abutment adapted to engage said auxiliary door for limiting closing movement thereof when elevated and a stop spaced rearwardly from said abutment adapted to engage said auxiliary door to permit opening movement thereof when lowered and unlocked to a predetermined amount.

3. As an article of manufacture, means for a railway house car having a supporting track and main and auxiliary sliding lift doors supported upon said track, said means comprising a channel shaped member having a portion adapted to be secured to the underframe of said car and a member secured to and extending upwardly from said channel shaped member, said latter member being adapted to engage said auxiliary door when elevated for the purpose set forth.

4. As an article of manufacture, means for a railway house car having a supporting track and main and auxiliary sliding lift doors supported upon said track, said means comprising a channel shaped member adapted to be secured to the underframe of said car, said channel shaped member carrying spaced flanges, one of said flanges being adapted to engage and limit closing movement of said auxiliary door when elevated and the other of said flanges being spaced rearwardly from said first mentioned flange and being adapted to engage said auxiliary door when lowered and unlocked to permit opening movement thereof to a predetermined amount.

5. As an article of manufacture, a channel shaped member for a railway house car having a supporting track and main and auxiliary sliding lift doors supported upon said track, said member having an inner leg adapted to be secured to the underframe of said car, an outwardly extending web and an outer leg, and a member having a portion secured to said outer leg and spaced upwardly extending flanges, one of said flanges being adapted to engage and limit closing movement of said auxiliary door when elevated and the other of said flanges being spaced rearwardly from said first mentioned flange and being adapted to engage said auxiliary door when lowered and unlocked to permit opening movement thereof to a predetermined amount.

6. As an article of manufacture a channel shaped member for a railway house car having a supporting track and main and auxiliary sliding lift doors supported upon said track, said member having a web adapted to be secured to the underframe of said car and outwardly extending legs, the lower of said legs having a flange, a member secured to said flange and extending upwardly through the upper leg to provide an abutment adapted to engage and limit closing movement of said auxiliary door when elevated and a member secured to and projecting above said upper leg in rearwardly spaced relationship to said second mentioned member adapted to engage said auxiliary door when lowered and unlocked to permit opening movement thereof to a predetermined amount.

7. In a railway house car having main and auxiliary sliding lift doors adapted to be locked together in closed position and a post secured to the inside of the auxiliary door at the front vertical margin thereof, means carried by the upper portion of said post, an inwardly extending member on said car, said post means engaging behind and being freely movable along said member when said auxiliary door is closed, and an abutment member secured to said car below said doors, said abutment member having a flange, one side of said flange being engaged by said auxiliary door when elevated to limit closing movement thereof, said auxiliary door when closed being free of engagement with the opposite side of said flange, said flange overlapping said main and auxiliary doors when said doors are closed.

8. In a railway house car having main and auxiliary sliding lift doors adapted to be locked together in closed position and a post secured to the inside of the auxiliary door at the front vertical margin thereof, means carried by the upper portion of said post, an inwardly extending member on said car, said post means engaging behind and being freely movable along said member when said auxiliary door is closed, and an abutment member secured to said car below said doors, said abutment member having a flange, one side of said flange being engaged by said auxiliary door when elevated to limit closing movement thereof, said auxiliary door when closed being free of engagement with the opposite side of said flange, said flange overlapping said main and auxiliary doors when said doors are closed, said abutment member having a lug spaced rearwardly from said flange, said lug permitting only a limited amount of opening movement of said auxiliary door when unlocked.

9. In a railway house car having main and auxiliary sliding lift doors adapted to be locked together in closed position and a post secured to the inside of the auxiliary door at the front vertical margin thereof, means carried by the upper portion of said post, an inwardly extending member on said car, said post means engaging behind and being freely movable along said member when said auxiliary door is closed, and an abutment member secured to said car below said doors, said abutment member having a flange, one side of said flange being engaged by said auxiliary door when elevated to limit closing movement thereof, said auxiliary door when closed being free of engagement with the opposite side of said flange, said flange overlapping said main and auxiliary doors when said doors are closed, and means on said main door extending transversely of and adjacent to said opposite side of said flange when said main door is closed for the purpose set forth.

10. In a railway house car having main and auxiliary sliding lift doors adapted to be locked

together in closed position, a member on said car, means on said auxiliary door adjacent to the forward upper corner thereof engaging behind and being freely movable along said member when said auxiliary door is closed, and an abutment member secured to said car below said doors, said abutment member having a flange, one side of said flange being engaged by said auxiliary door when elevated to limit closing movement thereof, said auxiliary door when closed being free of engagement with the opposite side of said flange, said flange overlapping said main and auxiliary doors when said doors are closed.

11. In a railway house car having a track and main and auxiliary sliding lift doors supported on said track and adapted to be locked together when closed, a member on said car, means on said auxiliary door adjacent to the forward upper corner thereof engaging behind and being freely movable along said member when said auxiliary door is closed and a substantially Z-shaped abutment member secured to said car below said doors, said abutment member having a depending securing flange, an outwardly extending web and an upstanding flange, said track having a depending flange which is coped, said web extending through said cope to dispose said upstanding flange in overlapping relationship with said main and auxiliary doors when said doors are closed, one side of said upstanding flange being engaged by said auxiliary door when elevated to limit closing movement thereof, said auxiliary door when closed being free of engagement with the opposite side of said upstanding flange.

12. In a railway house car having a track and main and auxiliary sliding lift doors supported on said track and adapted to be locked together when closed, a member on said car, means on said auxiliary door adjacent to the forward upper corner thereof engaging behind and being freely movable along said member when said auxiliary door is closed, and a substantially Z-shaped abutment member secured to said car below said doors, said abutment member having a depending securing flange, an outwardly extending web, an upstanding flange, and a lug spaced rearwardly from said upstanding flange, said track having a depending flange which is coped, said web extending through said cope to dispose said upstanding flange in overlapping relationship with said main and auxiliary doors when said doors are closed, one side of said upstanding flange being engaged by said auxiliary door when elevated to limit closing movement thereof, said auxiliary door when closed being free of engagement with the opposite side of said upstanding flange, said lug permitting only a limited amount of opening movement of said auxiliary door when unlocked.

THORVALD MADLAND.
